UNITED STATES PATENT OFFICE.

WALTER V. TURNER, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA.

AUTOMATIC SAND-VALVE DEVICE.

1,120,766.

Specification of Letters Patent. Patented Dec. 15, 1914.

Application filed March 18, 1913. Serial No. 755,067.

To all whom it may concern:

Be it known that I, WALTER V. TURNER, a citizen of the United States, residing at Edgewood, in the county of Allegheny and 5 State of Pennsylvania, have invented new and useful Improvements in Automatic Sand-Valve Devices, of which the following is a specification.

This invention relates to sanding devices, 10 and more particularly to a sanding device for automatically sanding the rails when the brakes are applied.

The principal object of my invention is to provide a sanding valve device for automatically sanding the rails both in service 15 and emergency applications of the brakes and adapted to permit either the service or the emergency sanding to be cut out.

According to my invention, a valve device 20 is provided having one sanding position which is assumed upon a gradual service reduction in train pipe pressure and another sanding position to which the parts move upon a sudden emergency reduction in train 25 pipe pressure. The operating piston of the sanding valve device is subject to the opposing pressures of the train pipe and the sanding reservoir and when the piston is in service sanding position there is some possibility of fluid leaking around the piston 30 from the sanding reservoir to the train pipe. If this happens, the brakes might be released during a brake application by the increase in train pipe pressure thus produced, particularly if the service sanding is cut out, so 35 that no fluid is supplied from the sanding reservoir for sanding purposes. According to my invention, in order to prevent leakage from the sanding reservoir to the train pipe 40 in the service sanding position, I provide means for sealing communication from the sanding reservoir to the train pipe.

In the accompanying drawing; Figure 1 is a diagrammatic view of a car air brake 45 equipment with my improvement applied thereto; Fig. 2 a central sectional view of a sand valve device embodying my invention, and showing the parts in normal position; Fig. 3 a similar view, showing the parts in the position 50 assumed upon making a service application of the brakes; and Fig. 4 a similar view, showing the parts in the position assumed when an emergency application of the brakes is made.

The air brake equipment shown in Fig. 1 55 of the drawing is of the ordinary type comprising a brake cylinder 1, auxiliary reservoir 2, and triple valve device 3 connected to the train pipe 4, and according to my invention a sand valve device 5 is provided which 60 is connected by pipe 6 to the train pipe 4.

The sand valve device 5 may comprise a casing having a piston chamber 7 connected by passage 8 with pipe 6 leading to the train pipe and containing piston 9, and having a 65 valve chamber 10 connected by pipe 11 to a sand reservoir 12 and containing a slide valve 13 adapted to be operated by the piston 9.

Leading to the seat of slide valve 13 is a 70 passage 14 connected to pipe 15 which communicates with a sand box, indicated diagrammatically in Fig. 1 by the reference numeral 16, and adapted to supply sand to the rails in service applications of the 75 brakes. Another passage 17 leads to the seat of the slide valve 13 and communicates with pipe 18, also connected to the sand box 16 and adapted to supply sand to the rails in an emergency application of the brakes. 80

The piston 9 and slide valve 13 have two operating positions, a service sanding position to which the parts move upon a gradual reduction in train pipe pressure and an emergency sanding position to which the 85 parts move upon a sudden reduction in train pipe pressure or a reduction below a predetermined degree, and in order to limit the movement of the parts upon a gradual reduction in train pipe pressure a yielding 90 stop device is provided for the piston 9. This stop device preferably comprises a sleeve member 20 having a seat ring 21 upon which an annular rib 22 of the piston 9 is adapted to seat. Said sleeve fits snugly 95 within a bore in a section 23 secured intermediate the casing proper and the cap 24.

The outer end of the sleeve 20 is provided with an annular flange portion 25 adapted to seat on the gasket 26 between the section 100 23 and cap 24 and thereby form a seal for preventing flow of air from the piston chamber 7 around the sleeve 20 to the train pipe.

A spring 27 tends to maintain the sleeve 20 in position with the flange 25 seated, by 105 its action on a stem 28 which bears against the sleeve.

In operation, when fluid is supplied to

the train pipe, the sanding reservoir is charged with fluid under pressure through passage 8, port 29, passage 30, piston chamber 7, and feed groove 31 around piston 9, 5 the piston 9 and slide valve 13 having moved to the position shown in Fig. 2. In this position the passages 17 and 14 are closed by the slide valve 13.

If a gradual reduction in train pipe pressure is made to effect a service application 10 of the brakes, the pressure is also reduced in piston chamber 7 and the piston 9 thereupon moves to service position, as shown in Fig. 3, in which the piston seats on the 15 seating ring 21 of the sleeve 20. In this position, a port 32 in the slide valve 13 registers with passage 14, so that fluid under pressure from the sanding reservoir 12 is supplied to the sand box 16, causing sand 20 to be delivered to the rails, the tension of the spring 27 being sufficient to prevent further outward movement of the piston under gradual reductions in train pipe pressure, unless the train pipe pressure is reduced to 25 a predetermined low degree, for example, the spring 27 may be designed to hold the piston in the service sanding position until the train pipe pressure is reduced to forty pounds, when a further reduction will cause 30 the movement of the parts to emergency position.

It will be understood that the sanding valve device operates in a manner similar to a triple valve in that a reduction in fluid 35 pressure on the reservoir side by flow to the said box causes the piston to move the valve 13 and lap the port 32, if such reduction should equal or slightly exceed the reduction in train pipe pressure.

40 If a sudden reduction in train pipe pressure is made, the piston 9 is shifted to the emergency sanding position, as shown in Fig. 4 of the drawing, compressing the spring 27. In this position, the port 19 in 45 the slide valve 13 registers with passage 17 and fluid from the sanding reservoir is thereupon supplied to the sand box 16 to effect the sanding of the rails.

When sanding in service is not desired, 50 the service sanding passage 14 is plugged up, so that when the sand valve parts move to the service sanding position, no fluid is supplied to the sand box. In this case, it will be noted that the piston 9 is sealed 55 against the seat 21 of the sleeve 20 when the piston is in the service sanding position and the flange 25 is also seated on the gasket 26. A double seal is thus provided, which effectually prevents leakage of fluid under 60 pressure from the sanding reservoir to the train pipe, so that there is no possibility of the brakes releasing while applied.

Emergency sanding may also be cut out 65 by plugging the passage 17, but this is not usually desired.

Having now described my invention, what I claim as new and desire to secure by Letters Patent, is:

1. The combination with a fluid pressure brake, of a sanding valve device automatically movable to one position for effecting the sanding of the rails upon a service application of the brakes and to another position for effecting the sanding of the rails upon an emergency application of the 75 brakes.

2. The combination with a fluid pressure brake having a train pipe and means operated by a gradual reduction in train pipe pressure for effecting a service application 80 of the brakes and by a sudden reduction in train pipe pressure for effecting an emergency application of the brakes, of a sanding valve movable to one sanding position upon a gradual reduction in train pipe pressure and to another sanding position upon a sudden reduction in train pipe pressure. 85

3. The combination with a fluid pressure brake having a train pipe, of a sanding valve device comprising valve means having 90 two positions for effecting the sanding of the rails, a piston operated upon a gradual reduction in train pipe pressure for moving said valve means to one sanding position and upon a sudden reduction in train pipe pressure for moving said valve means to the other sanding position and means for closing communication from said piston to the train pipe in the first mentioned sanding position. 95

4. The combination with a fluid pressure brake having a train pipe, of a sanding valve device comprising valve means having two positions for effecting the sanding of the rails, a piston operated upon a gradual reduction in train pipe pressure for moving said valve means to one sanding position and upon a sudden reduction in train pipe pressure for moving said valve means to the other sanding position, a yielding stop 105 device for opposing the movement of said piston from the first mentioned sanding position and means for preventing flow of fluid from the piston to the train pipe in said position. 110

5. The combination with a fluid pressure brake having a train pipe and means operated upon a gradual reduction in train pipe pressure for effecting a service application 120 of the brakes and upon a sudden reduction in train pipe pressure for effecting an emergency application of the brakes, of valve means having a service sanding position and an emergency sanding position, a piston subject to the opposing pressures of the train pipe and a reservoir and operated upon a gradual reduction in train pipe pressure for moving said valve means to the service sanding position and upon a sudden reduction in train pipe pressure for moving 125 130

said valve means to emergency sanding position, a yielding stop for defining the service sanding position of said piston, and means for sealing communication from said piston 5 to the train pipe in the service sanding position to prevent flow of fluid from the reservoir to the train pipe.

6. A sanding valve device comprising a valve for controlling the sanding and a piston subject to opposing fluid pressures and 10 adapted to shift said valve to one sanding position upon a partial traverse and to another sanding position upon a further traverse and a yielding member for defining the 15 first mentioned position of the piston and provided with a seat for said piston to prevent leakage of fluid from said piston.

7. A sanding valve device comprising a

valve for controlling the sanding and a piston subject to opposing fluid pressures and 20 adapted to shift said valve to one sanding position upon a partial traverse and to another sanding position upon a further traverse and a yielding member for defining the first mentioned position of the piston and 25 provided with a seat for said piston to prevent leakage of fluid from and around said piston and also provided with a seat to prevent leakage from said piston past said yielding member.

In testimony whereof I have hereunto set my hand.

WALTER V. TURNER.
